UNITED STATES PATENT OFFICE.

WILLIAM GOLDIE, JR., OF BAY CITY, MICHIGAN.

RAILWAY-JOINT PLATE.

1,082,022.

Specification of Letters Patent. Patented Dec. 23, 1913.

Application filed January 6, 1911. Serial No. 601,184.

To all whom it may concern:

Be it known that I, WILLIAM GOLDIE, Jr., a resident of Bay City, in the county of Bay and State of Michigan, have invented 5 a new and useful Improvement in Railway-Joint Plates; and I do hereby declare the following to be a full, clear, and exact description thereof.

My invention relates to railway track joints and supports. Its object is to provide a combined support for two adjoining rails at their junction between the ties and tie plate or rail fastening for supporting and holding the rails on the two adjacent 15 ties.

In other words, the object of my invention is to provide in one rigid structure a rail fastening device comprising two tie plates each supporting and holding two adjoining rails on the two adjacent ties, and an integral connecting portion forming a rail support underneath the rail joint.

The general nature of my invention appears from the above statement of its object, the structure provided being regarded by me as broadly new as an article of manufacture.

While rail joints, fish plates and chairs have been constructed in a great number 30 of forms, so far as I know, these devices have always merely fastened together two adjoining rails between the ties, even if the fastening device is itself supported upon one or more of the ties; or have supported 35 the rails at their junction on a given tie, thus performing the holding and wear-saving function of the typical tie plate, as well as the track alining function of the rail joint, but only, in this case, where the joint 40 is upon the tie.

It is now well known in railway practice that the preferable form of rail junction is the open one, where the two rail ends join between the ties; and by my invention I 45 provide in a unitary and preferably integral structure, a rail joint support and tie plates upon the adjoining ties, my invention comprising preferably a truss support provided with depending flanges beneath the 50 rail junction and also an improved form of claw tie plate having all the advantages of the well known claw plate type as well as preferably the claw construction described in my United States Letters Patent No. 884,578

of April 14, 1908, and No. 911,230 of Feb. 55 2, 1909.

In the accompanying drawings Figure 1 is a side view of a rail joint illustrating one form of my invention as applied thereto. Fig. 2 is a vertical section on the line 2—2 60 Fig. 1. Fig. 3 is a top perspective view of the railway joint plate illustrated in Figs. 1 and 2, and Fig. 4 is a bottom perspective view of the same.

The adjoining rails 1 and 2 illustrated 65 in Figs. 1 and 2 are supported upon the adjacent ties 3 and 4, having their junction 5 between the same. The joint plate 6 illustrated comprises the rail joint supporting portion 7 and the tie plate portions 8 and 9 70 integral therewith. The supporting portion 7 is preferably provided with the depending flanges 10 extending preferably the greater portion of the distance between the ties 3 and 4 and thereby forming with the connecting portion 7 proper a truss support 75 for the rail joint. The tie plate portions 8 and 9 extend beneath the rails 1 and 2, supporting them upon the ties 3 and 4, respectively, and thereby increasing the life 80 of the said ties, and performing the other well known functions of a tie plate. I prefer to provide the tie plate portions 8 and 9 with the claws or pins 11 which have 85 their greatest horizontal dimension transverse to the tie or side thrust on the rail during traffic. The claws 11 are arranged on each side of the rail base, as illustrated in Fig. 2, and may be of any desired depth, the outer set of claws 11' in each tie plate 90 portion and the inner set of claws 11'' each having a tapered or sheared point portion 12 and a substantially flat face 13, arranged preferably facing outwardly or away from the rail base. I am enabled to provide 95 claws of this nature by inserting and riveting them in the form of pins in the slots 14 punched in the joint plate preferably in the grooves 15 between the slight rib 16 rolled in said plate. The manner of inserting the said claws or pins is described more 100 particularly in my said United States Letters Patent No. 884,578 and No. 911,230 both above noted, and it is sufficient here to mention that the claws may thereby be arranged in any desired position or fashion 105 and any required number may be employed either below or outside the rail base 17.

The shoulder 18 extends preferably the entire length of the joint plate, serving not only as a holding means for the rail base 17, but also as an upper chord in the trussed 5 connecting portion 7 under the rail joint.

The integral railway joint plate comprising the preferred form of my invention may be conveniently manufactured in the form of a rolled section. The shoulder or flange 10 is rolled on the upper face of the plate bar, and the depending flanges 10 are rolled on its lower face, the slight flanges 16 being also rolled thereon when employed. The succeeding operations in manufacture consist merely in shearing out the portions of 10 the flanges containing the depending flanges 16, so as to leave the same of proper length to extend between two ties of standard or any desired spacing; shearing the bar to 15 form the separated plates; and punching the same to provide the pin or claw slots 14 and the desired number of spike holes 18, four of such spike holes and four spikes 19 being illustrated in the accompanying drawings in 20 each tie plate portion 3 and 9. Any desired form of manufacture, however, may of course be employed to produce the article of 25 my invention.

It will thus be seen that by a simple process of manufacture, I am enabled by my invention to provide a device which has the mechanical advantages of a truss support capable of resisting great downward stresses and vibrations at the rail joint as well as the 30 tie plate support fastening the rail upon the adjacent ties and saving said ties, the said tie plate portions being preferably provided with claws offering great resistance to side thrust in traffic and fastened in the plate 35 portion in accordance with the inventions patented to me as above specified. It will be understood, however, that other forms of tie plate portions and other constructions of rail joint portion may be employed within 40 the spirit of my invention which comprises broadly a combined rail joint and tie plate as herein set forth.

If desired, the fish plates 20 and 21 may be employed to further secure the rail joint and 45 stiffen the rails 1 and 2 at their junction. The provision of fish plates in combination with the device of my invention is not essen-

tial, especially where the improved form of tie plate portion specifically described is employed, although the entire combination provides an even more nearly perfect rail joint and supporting device. The fish plates 20 and 21 are illustrated as of two somewhat different forms being connected by the bolts 22 in the regular manner. It is also apparent that my invention may be employed to support and fasten one rail upon two adjacent ties, the connecting portion between the ties serving to stiffen the rail where the traffic is especially heavy, or it is desired for 55 even reason to provide an especially rigid and even road bed.

What I claim is:

1. A railway joint plate comprising a joint supporting portion adapted to extend 70 underneath two adjoining rail bases, and two tie plate portions integral therewith and supporting the rail bases on the two adjacent ties, an integral shoulder extending longitudinally to abut against the rail bases and 75 stiffen the joint portion, a depending flange on the joint supporting portion adapted to extend between the ties and complete with the shoulder a truss support for the rail joint and gripping ridges extending 80 throughout the length of the device at the opposite longitudinal edges thereof.

2. In rail fastenings, the combination with two adjoining rails and two adjacent ties, of a railway joint plate comprising two tie 85 plate portions adapted to support the rails upon the ties and provided with claws secured thereto and having their broad faces arranged transversely of the ties to prevent movement thereon and means for holding 90 the rails upon said tie plate portions, and an integral joint supporting portion connecting said tie plate portions and provided with depending flanges to stiffen the rail joint gripping ridges extending throughout the 95 length of the device at the extreme opposite edges thereof, said plates, ridges and flanges being formed from a bar rolled to shape.

In testimony whereof I, the said WILLIAM GOLDIE, Jr., have hereunto set my hand.

WILLIAM GOLDIE, Jr.
